UNITED STATES PATENT OFFICE.

IVAR S. SALO AND HENRY J. LUND, OF VIRGINIA, MINNESOTA.

LOADING APPARATUS.

1,260,459.

Specification of Letters Patent. Patented Mar. 26, 1918.

Application filed November 3, 1917. Serial No. 200,083.

To all whom it may concern:

Be it known that we, IVAR S. SALO and HENRY J. LUND, citizens of Russia, residing at Virginia, in the county of St. Louis and 5 State of Minnesota, have invented certain new and useful Improvements in Loading Apparatus, of which the following is a specification, reference being had to the accompanying drawings.

10 This invention relates to certain improvements in loading apparatus and has relation more particularly to a device of this general character especially designed and adapted for use in connection with ore, and it is an 15 object of the invention to provide an apparatus of this general character having novel and improved means whereby the ore or other material may be readily and conveniently delivered to a car or other vehicle.

20 The invention also has for an object to provide a novel and improved apparatus of this general character including a movable supporting truck and a loading mechanism mounted upon the truck and movable in a 25 direction substantially transverse of the direction of travel of the supporting truck.

It is also an object of the invention to provide a novel and improved apparatus of this general character including a portable 30 supporting truck and a loading mechanism carried by the truck and mounted for movement independently thereof together with means carried by the loading mechanism for imparting movement to said mechanism and 35 also adapted to be operatively engaged with the truck for driving said truck.

The invention consists in the details of construction and in the combination and arrangement of the several parts of our 40 invention wherein certain important advantages are attained and the device rendered simpler, less expensive and otherwise more convenient and advantageous for use, as will be hereinafter more fully 45 set forth.

The novel features of our invention will hereinafter be definitely claimed.

In order that our invention may be the better understood we will now proceed to describe the same with reference to the accompanying drawings wherein:

Figure 1 is a view in side elevation of a loading mechanism constructed in accordance with an embodiment of our invention;

Fig. 2 is a vertical sectional view taken 55 through the device as herein embodied;

Fig. 3 is a view in top plan of the supporting truck as herein included;

Fig. 4 is a fragmentary view in elevation illustrating one of the supporting members 60 for an extended portion of the trackway as embodied in the supporting truck;

Fig. 5 is a sectional view taken substantially on the line 5—5 of Fig. 2;

Fig. 6 is a horizontal sectional view taken 65 through the lower portion of the mechanism mounted upon the supporting truck, the supporting truck being omitted for clarity of disclosure;

Fig. 7 is an enlarged sectional view taken 70 substantially on the line 7—7 of Fig. 6;

Fig. 8 is a view in side elevation of the structure disclosed in Fig. 7 with a part omitted and certain of the shafts in section;

Fig. 9 is a fragmentary view partly in 75 elevation and partly in section illustrating a portion of the mechanisms for transmitting power to the supporting truck.

Fig. 10 is a view in top plan of the inclined beams herein employed together with 80 certain of the parts co-acting directly therewith;

Fig. 11 is a fragmentary view in top plan illustrating a slightly modified form of invention as relates to the mounting for the 85 buckets; and

Fig. 12 is a diagrammatic view in elevation showing our improved apparatus in position for work together with the car co-acting therewith.

90

As disclosed in the accompanying drawings T denotes a trackway extending in a direction toward the material M to be loaded and traveling on the trackway T is the supporting truck S.

95

As herein embodied the supporting truck S comprises the side sills 1 connected at their opposite ends by the transversely disposed plates 2. Mounted upon the plates 2 is the arcuate trackway A extending transversely 100 of the truck S and extending a predetermined distance therebeyond. The trackway A com-

prises a plurality of rails 3 detachably connected as at 4 and the rails at the opposite ends of the trackway are connected by the brace bars 5. Loosely disposed through each end portion of the bars 5 is the vertically disposed shank 6 having at its lower end the fork 7 affording a mounting for the ground engaging wheel 8. The shank 6 is normally held against movement independently of the bar 5 by the clamping screw 9 threaded through the bar 5 and co-acting with the shank 6 in a conventional manner. The shank 6 together with the wheels 8 serve as supports for the outer portions of the trackway T and the vertical adjustment of the shank 6 readily permits compensation for any inequalities in the ground or other surface with which the wheels 8 engage.

Rotatably supported by the side sills 1 adjacent the rear end thereof is a transversely disposed axle 10 having fixed to its opposite end portions the flanged wheels 11 riding upon the trackway A. The forward end portion of each of the sills 1 is provided in its lower marginal portion with an open recess 12 in which is slidably mounted for vertical movement a bearing block 14. As is particularly illustrated in detail Fig. 5 the vertical walls of the recess 12 and the adjacent walls of the bearing block 14 are provided with interlocking tongues and grooves as indicated at 15 whereby the block 14 is maintained in applied position within the recess 12. Threaded through the upper edge 35 of the sill 1 is a jackscrew 16 having its lower end in contact with the upper face or wall of the bearing block 14 so that when the screw 16 is moved downwardly the forward end portion of the sill 1 will be elevated and vice versa. Each of the bearing blocks 14 serves as a mounting for the forward axle 17 having operatively engaged with its opposite end portions the flanged wheel 18 riding upon the trackway T.

19 denotes a brake beam provided at its opposite ends with the shoes 20 coacting with the wheels 11 for locking the truck S against movement. The beam 19 midway its length is provided with the forwardly directed arm 21 pivotally engaged as at 24 with a side sill 1. The opposite end portion of the rock lever 23 is pivotally engaged as at 25 with the piston rod 26 adapted to be reciprocated in any desired manner but preferably through the medium of air and in the same manner as employed in the Westinghouse straight line system. It is to be understood however that if preferred any type of brake mechanism may be employed which will successfully meet the requirements of practice.

At a predetermined point intermediate the side sills 1 the shaft 10 has fixed thereto a sprocket wheel 27 around which is directed the sprocket chain 28 also disposed around a

sprocket wheel 29 fixed to a shaft 30 disposed transversely of the truck S, and rotatably supported by the side sills 1. One end portion of the shaft 30, outwardly of the adjacent sill 1, is provided with a gear wheel 31 for a purpose which will hereinafter be more particularly referred to.

The loading mechanism proper comprises a pair of forwardly and downwardly inclined side beams 32 maintained in predetermined spaced relation by the cross strips 33. Depending from the side beams 32 adjacent the opposite ends thereof are the legs 34 provided at their lower ends with the flanged wheels 35 riding upon the trackway A carried by the supporting truck S.

Rotatably supported at the opposite end portions of the beams 32 are the transversely disposed shafts 36. Fixed to each of the shafts 36 adjacent each end thereof is a sprocket wheel 37 around which is disposed an endless sprocket chain 38. Suitably engaged with the chain 38 are the buckets 39. It is believed to be self evident that in practice, two chains 38 are employed.

The upper shaft 36 has operatively engaged therewith the sprocket chain 40 which extends downwardly and passes around the sprocket wheel 41 carried by the transversely disposed shaft 42 rotatably engaged with the longitudinally disposed horizontal sills 43. The sills 43 are suitably supported by the legs 34 adjacent the lower ends thereof. At a point substantially midway between the sills 43, the shaft 42 has fixed thereto a gear wheel 44 operatively engaged with the gear wheel 45 carried by the driving shafts 46 of the engine E which may be of an internal combustion type or of any other type which will operate with convenience and facility. The engine E as herein disclosed is supported on the transverse cross beam 47 suitably engaged with the beams 43 adjacent the rear ends thereof.

The end portion of the shaft 42 remote from the sprocket wheel 41 is provided with a second sprocket wheel 48 around which is disposed a sprocket chain 49 which is also directed around a sprocket wheel 50 fixed to the shaft 51. The shaft 51 is rotatably supported by the forks 52 arranged at the lower end of the arm 53 depending from an adjacent side beam 32 and as is particularly illustrated in Figs. 6 and 7 the sprocket wheel 50 is positioned between the forks 52.

The outer end portion of the shaft 51 is provided with a pinion 54 which is adapted to mesh with either the gear 55 or the gear 56 rotatably supported between the opposite end portions of the spaced plates 57. The plates 57 are mounted for rocking movement upon the shaft 58 rotatably supported by the forks 52 and the shaft 58 is provided at its inner end with a beveled pinion 59 con-

stantly in mesh with a beveled gear 60 fixed to the axle 61 of an adjacent flanged wheel 35. The opposite or outer end portion of the shaft 58 has fixed thereto a pinion 62 positioned between the plates 57. The gear 62 is constantly in mesh with the gear 56 and with an idle pinion 63. The pinion 63 is constantly in mesh with the gear 55. When the gears 55 and 56 are in neutral position or free of the gear 54 the loading mechanism will be maintained in a fixed position upon the trackway A but when it is desired to move the mechanism laterally of the supporting truck S in either direction the gear 55 or 56 will be caused to mesh with the gear 54. In order to impart the requisite rocking movement to the plates 57 to cause the gear 55 or 56 to mesh with the gear 54 I provide one of the plates 57 with the depending extension 64. Pivotaly engaged with the extension 64 is a rod 65 which extends rearwardly and has its rear end portion pivotaly engaged as at 66 with the lower end portion of the upstanding lever 67 pivotaly mounted as at 68 with the outstanding platform 69 arranged at the inner end portion of the adjacent sill 43. The lever 67 extends through a suitable opening 70 produced in the platform 69. The lever 67 is also provided with a latch mechanism 71 of a conventional type co-acting with the upstanding rack 72 carried by the platform 69.

In operation the upper stretch of each of the chains 38 travels rearwardly so that the buckets 39 will be caused to properly engage the material M so that the same may be discharged within the car C or other vehicle to be loaded and it will be self evident that the lower portion of the beams 32 may be raised or lowered as the occasion may require through the medium of the jackscrew 16 hereinbefore referred to. Our improved machine is adapted for use within a mine or exteriorly thereof and when entering within a drift the rails 3 are separated as at 4 so that the extended portions of the trackway T will afford no obstruction to the entrance of the apparatus. The shaft 42 has also fixed thereto a sprocket wheel 73 and around which is disposed a sprocket chain 74 which is also directed around a sprocket wheel 75 fixed to the transverse shaft 76 supported by the wheels 43 and preferably positioned directly below the cross beam 47. An end portion of the shaft 76 has fixed thereto a gear wheel 77 positioned between the plate 78 mounted for rocking movement upon the shaft 76. The gear wheel 77 is constantly in mesh with a gear 79 and an idle gear 80. The gear 80 is constantly in mesh with the gear 81. The gears 79, 80 and 81 are rotatably supported by the plates 78 and positioned therebetween. Upon requisite rocking movement being imparted to the plate

78 the gear 79 or 81 is caused to mesh with the gear 31 hereinbefore referred to so that the axle 10 may be caused to rotate to move the supporting truck S either forwardly or backwardly. It is to be understood however that before the gear 79 or 81 can be caused to mesh with the gear 31 the loading mechanism must be caused to assume a position directly above the truck S.

In order to impart the requisite rocking movement to the plates 78 one of said plates 75 is provided with an upstanding extension 82 having pivotaly engaged therewith a rod 83 which is also pivotaly engaged with the lower extremity of a rocking lever 84 rotatably supported by the platform 69 and extending through an opening 85 in said platform. The lever 84 is also provided with a suitable latch mechanism coacting with the upstanding rack 86 carried by the platform 69.

As is particularly illustrated in Fig. 10, the lower end portions of the beams 32 are offset inwardly as indicated at 87 so that the lower extremities 89 of said beams 32 are separated a distance less than the length of 90 the buckets 39 so that said buckets may have a more effective action upon the material M.

In Fig. 11 we illustrate a slightly modified form of mounting for the buckets and wherein are employed the links 90 connected by the equidistantly spaced pintles 91 and which pintles are adapted to co-act with the sprocket wheels 36 to assure the requisite travel of the buckets.

It is also to be noted in Fig. 12 that the car C also travels on the trackway T so that the same may be properly moved relative to the apparatus.

From the foregoing description, it is thought to be obvious that a loading apparatus constructed in accordance with our invention is particularly well adapted for use by reason of the convenience and facility with which it may be assembled and operated and it will also be obvious that our invention is susceptible of some change and modification without materially departing from the principle and spirit thereof and for this reason we do not wish to be understood as limiting ourselves to the precise arrangement and formation of the several parts herein shown in carrying out our invention in practice except as hereinafter claimed.

We claim:

1. A loading apparatus comprising a portable truck, a loading mechanism mounted upon the truck and movable in a direction angular to the direction of travel of the truck, means carried by the loading mechanism for imparting movement to said mechanism relative to the truck, and means co-acting with said last named means for

imparting movement to the portable truck independently of the movement of the loading mechanism when the loading mechanism is at a predetermined position upon the 5 truck.

2. A loading apparatus comprising a portable truck, a loading mechanism mounted thereon and movable independently of the truck, means for imparting movement to the 10 loading mechanism, and means co-acting with said last named means for imparting movement to the portable truck either forwardly or rearwardly when the loading mechanism is at a predetermined point on 15 the truck.

3. A loading apparatus comprising a portable truck, a loading mechanism mounted thereon and movable independently of the truck, means for imparting movement to the 20 loading mechanism, and means co-acting with said last named means and normally free therefrom for imparting movement to the portable truck when the loading mechanism is at a predetermined point on 25 the truck.

4. A loading apparatus comprising a portable truck, a loading mechanism mounted thereon and movable independently of the truck, means for imparting movement to the 30 loading mechanism, means co-acting with said last named means and normally

free therefrom for imparting movement either forwardly or rearwardly to the portable truck when the loading mechanism is at a predetermined point on the truck, and means for raising or lowering an end portion 35 of the truck.

5. A loading apparatus comprising a portable truck, a loading mechanism mounted upon the truck and movable in a direction transversely of the direction of travel of the truck, said loading mechanism including buckets traveling in an endless path and in a vertically inclined direction, means for moving the loading mechanism transversely 40 of the truck, means co-acting with the last named means and normally free therefrom for imparting movement to the truck either forwardly or rearwardly when the loading mechanism is at a predetermined position 45 upon the truck, and means for raising and lowering the end portion of the truck adjacent the lower end portion of the path of travel of the buckets.

In testimony whereof we hereunto affix 55 our signatures in the presence of two witnesses.

IVAR S. SALO,
HENRY J. LUND.

Witnesses:

Mrs. M. TURPPA,
JAS. E. TURPPA.
